UNITED STATES PATENT OFFICE.

HOWARD T. INGHRAM, OF KANSAS CITY, MISSOURI, ASSIGNOR TO HOWARD T. INGHRAM, GEORGE ZIMMERMAN, AND P. G. OWENS, JOINT TRUSTEES FOR U-WANT-A PRODUCTS COMPANY.

HOLDING IMPLEMENT.

1,420,925.

Specification of Letters Patent. Patented June 27, 1922.

Application filed June 14, 1921. Serial No. 477,535.

To all whom it may concern:

Be it known that I, HOWARD T. INGHRAM, a citizen of the United States, residing at Kansas City, in the county of Jackson and State of Missouri, have invented certain new and useful Improvements in Holding Implements, of which the following is a specification.

This invention relates to certain new and useful improvements in holding devices of the type disclosed in my Patent No. 1,256,565 issued February 19, 1918, and it is an object of this invention to provide an improved means for rigidly holding, at any angle with respect to the handle, such household articles as brooms, floor brushes, wall dusters and brushes, scrubbing brushes, window washing brushes and driers, dust cloths for ceilings, walls and woodwork, floor and oil 20 mops, etc.

Another object of the present invention is to provide a device of the character described, which is extremely simple in construction, each of the gripping members being designed in such manner that they may be cast integral, thus insuring a rigid and perfect section, the various parts of the device being reinforced in such manner as to insure long hard service.

Another object of this invention is to provide an efficient and simple means of the class described, which may be cast from such light metals as aluminum, thus insuring light weight and neatness of appearance.

A further object is to provide a device of this character which will successfully hold all these many household articles, thus saving to the user the expense of brush handles with all these various articles such as is the case at present.

In its more detailed nature, the invention resides in those features of construction, combination and arrangement of parts, all of which will be fully described and then be specifically pointed out in the appended claims, reference being had to the accompanying drawings, in which:

Figure 1 is a side elevation of the invention as applied to holding a broom.

Figure 2 is an end view of the same.

Figure 3 is a detail view showing the use of the implement for holding mops.

Figure 4 is a bottom plan view of one of the parts of which my invention is composed.

Figure 5 is an elevation of the same looking in the direction of the arrow in Figure 6.

Figure 6 is an end elevation of the parts shown in Figure 5.

Figure 7 is a detail section on the line 7—7 of Figure 5.

Figure 8 is a view similar to Figure 4 of a second part which mates with the parts shown in Figure 4.

Figure 9 is a view similar to Figure 5 of the parts shown in Figure 8.

Figure 10 is a view similar to Figure 6 of the parts shown in Figures 8 and 9.

Figure 11 is side elevation of the third of the parts constituting my invention.

Figure 12 is an elevation of the same taken at right angles to the view of Figure 11.

Figure 13 is a cross section on the line 13—13 of Figure 12.

Figure 14 is a top plan view.

Figure 15 is an elevation of the bar which is attached to brush backs and the like by which the same may be engaged or gripped by the device constituting the present invention.

Referring to the accompanying drawings in which like numerals and letters of reference indicate like parts in all of the figures, it will be observed that the present invention consists of three principal parts, the parts A and B which mate, and the part C which is adjustably and hingedly connected with the parts A and B and is itself adapted to be secured in the handle of the implement.

When the implement is to be used in connection with brushes or other stiff backed articles of that nature, a fourth part D is employed, which is secured to the back of the brush and forms a member that may be gripped by the jaws A and B of the implement.

It will be noticed especially by reference to Figures 8, 9 and 10 that the part A is provided with two rearwardly extending sides 1—1 that are adapted to fit astride the corresponding sides 1—1 of the part B (see Figures 4, 5 and 6), the sides 1 being provided with holes 7 and 8 through which passes the thumb screw 32 (see Figure 1) which causes the members 1 and 11 to be rigidly, though adjustably, secured to the part C.

It will also be noticed that the sides 1—1 extend through and under the body of the part A, as at 1^a, serving as guides for the sides 11—11 of the part B, thus maintaining 5 the two jaws in exact relation to one another, when in operation.

Reinforcing means 2 and 18, respectively, are provided for the backs of the parts A and B and, when assembled and closed together, these members compact, thus adding 10 to the appearance of the device.

The lower edge of the rib 4 of part A and the corresponding edge 4^x of part B are disposed to extend under the flanges 24 of the 15 brush attachment D, when in operative position, the edges of the flanges 24 being gripped within that space 3 and 13, the purposes of which is obvious.

It will also be noticed that reinforcing 20 parts 5^a are provided on either side of the member A and corresponding reinforcing parts 17 are provided on either side of the member B, thus preventing excessive wear at these points.

25 Those portions 11 of the part B are provided on the inside with a series of ratchets 16 which are disposed to engage the corresponding indentations 20 of the element or part C.

30 By this combination, the holder consisting of the elements A and B may be adjusted at any angle with respect to the handle and is maintained rigidly in position by means of the thumb screw 32.

35 The element C by which the jaws are mounted on the handle in an adjustable manner is best shown in Figures 11 and 12 of the drawings, by reference to which it will be observed that it is provided with a shoulder 22 disposed to contact the end of the handle and after being driven in place, is firmly united with the handle 36 by the ferrule 33 and a small rivet 34.

40 The shank 23 of the element C is of rectangular construction in order that it may be driven into a small hole without injury to the handle.

45 The attachment D is provided with ears 28 having holes 29 through which screws 29^a pass into the back of the article to be used. These ears, as will be noticed, are wide in construction, thus making the connection to the article to be used very rigid.

50 The sections 24 are the only parts gripped by the holder.

It will be noticed that upon loosening the thumb screw 35, the spring 10 will cause the jaws A and B to separate, thus releasing the article being used.

55 The spring 10 is preferably of the flat type and is placed between the sides 11 of element B and besides 1^a of element A, the rear portion of the spring being closed to the thumb screw 35, as best shown in Figure 2.

It will be seen that in order to secure or release the brush or other article being held by the jaws A and B, it is not necessary to change the angularity of the holder with relation to the handle.

As both members A and B are pivoted on the same bolt 32 and as the member A has its sides 1—1 smooth, it is quite convenient to release the article from the jaws A and B by simply loosening the thumb screw 35, the 75 spring 10 then functioning to separate the jaws to allow for the removal or insertion of the article.

The handle may be adjusted to any angle, as indicated by the arrows in Figure 1, by 80 simply loosening the thumb screw 32 sufficiently to enable the ratchet 16 to be changed in their location in the indentations 20.

Such articles as dust cloths, or mops, etc., (see Figure 3) may be folded up and placed 85 between the open jaws and, when tightened, will be just as permanent as the brush 30 which is provided with the part D.

From the foregoing description, taken in connection with the accompanying drawings, 90 it is thought the complete construction, operation and advantages of my invention will be readily understood by those skilled in the art.

What I claim is:

1. In an implement of the class described, a pair of coacting jaw members, each including parallel side plates and laterally extended portions having a gripping flange, a handle connecting member adapted for connection to a handle, a single means hingedly connecting said jaw member side plates to said handle connecting member and including means for interlocking one of said jaw members with said handle connecting member and for pivotally connecting the other of said jaw members with the first jaw member and handle connecting member, a spring carried by said jaw members for separating them and a thumb screw connecting said 100 jaw members for forcing them together against the action of said spring.

2. In an implement of the class described, two jaw members, each having upstanding side plates for connection to a handle, a handle connecting member with which said side plates cooperate, the side plates of one of said jaw members and said handle connecting member having interlocking elements, a thumb screw connecting the side 110 plates of said jaw members to said handle connecting member and to each other, with the side plates of one of said jaws hingedly mounted on said thumb screw for motion without disturbing the interlocked connection between the other of said plates and said handle connecting member, a spring 115 tending to separate said jaws and means for drawing said jaws together against the action of said spring.

3. In an implement of the class described, a pair of jaw members each in one piece and each comprising vertical parallel side plates, those of one jaw fitting within those of the other jaw and adapted to be pivotally connected together at their upper ends, opposed gripping elements at the lower ends of said jaw plates, a handle connecting element comprising a flat apertured head and a shank, said head adapted to fit between the side plates of said jaws, means pivotally connecting said side plates together to said head and including elements for adjustably and rigidly connecting said head and the adjacent side plates of one jaw together, the side plates of the other jaw being free for motion on the pivotal axis, and means for separating and closing said jaws respectively to release and grip the articles to be held.

4. In an implement of the class described, a pair of jaw members each in one piece and each comprising vertical parallel side plates, those of one jaw fitting within those of the other jaw and adapted to be pivotally connected together at their upper ends, laterally extending gripping elements at the lower ends of said jaw plates, a handle connecting element comprising a flat apertured head and a shank, said head adapted to fit between the side plates of said jaws, means pivotally connecting said side plates together to said head and including elements for adjustably and rigidly connecting said head and the adjacent side plates of one jaw together, the side plates of the other jaw being free for motion on the pivotal axis, means for separating and closing said jaws respectively to release and grip the articles to be held, the said laterally extending gripping element of one jaw matching that of the opposite jaw and said separating means comprising a flat loop spring held between said jaws below the closing means.

5. In an implement of the class described, a pair of jaw members each in one piece and each comprising vertical parallel side plates, those of one jaw fitting within those of the other jaw and adapted to be pivotally connected together at their upper ends, laterally extending gripping elements at the lower ends of said jaw plates, a handle connecting element comprising a flat apertured head and a shank, said head adapted to fit between the side plates of said jaws, means pivotally connecting said side plates together to said head and including elements for adjustably and rigidly connecting said head and the adjacent side plates of one jaw together, the side plates of the other jaw being free for motion on the pivotal axis, means for separating and closing said jaws respectively to release and grip the articles to be held, the said laterally extending gripping element of one jaw matching that of the opposite jaw, said separating means comprising a flat loop spring held between said jaws below the closing means, and said gripping element including inturned flanges forming abutments for the ends of said springs.

6. In an implement of the class described, a handle connecting member consisting of a flat apertured head and a shank, a thumb screw passing through the aperture of said head, a pair of jaw members each including a pair of side plates connected together by a web, the upper ends of said side plates being apertured to form ears to receive said thumb screw for pivotally connecting said jaws to said head, means on said head and said side plates cooperating with said thumb screw for rigidly and adjustably holding one of said jaws to said head while permitting the other jaw to swing on the pivotal axis toward and from the rigid jaw, a spring held between said side plates of the opposing jaw, a thumb screw passing through the webs of said jaws between said side plates for drawing them together against the tension of the spring, the lower ends of said jaws including laterally extended web portions terminating at the bottom in inturned gripping flanges substantially as shown and described.

7. In an implement of the class described, a handle connecting member consisting of a flat apertured head and a shank, a thumb screw passing through the aperture of said head, a pair of jaw members each including a pair of side plates connected together by a web, the upper ends of said side plates being apertured to form ears to receive said thumb screw for pivotally connecting said jaws to said head, means on said head and said side plates cooperating with said thumb screw for rigidly and adjustably holding one of said jaws to said head while permitting the other jaw to swing on the pivotal axis toward and from the rigid jaw, a spring held between said side plates of the opposing jaw, a thumb screw passing through the webs of said jaws between said side plates for drawing them together against the tension of the spring, the lower ends of said jaws including laterally extended web portions terminating at the bottom in inturned gripping flanges, and inturned matching flanges, the latter being recessed adjacent to the gripping flanges and enlarged to form reinforcements at the ends, substantially as shown and described.

8. In an implement of the class described, a handle connecting member consisting of a flat apertured head and a shank, a thumb screw passing through the aperture of said head, a pair of jaw members each including a pair of side plates connected together by a web, the upper ends of said side plates being apertured to form ears to receive said thumb screw for pivotally connecting said jaws to said head, means on said head and said side plates cooperating with said thumb screw for rigidly and adjustably holding one of said jaws to said head while permitting the other jaw to swing on the pivotal axis toward and from the rigid jaw, a spring held between said side plates of the opposing jaw, a thumb screw passing through the webs of said jaws between said side plates for drawing them together against the tension of the spring, the lower ends of said jaws including laterally extended web portions terminating at the bottom in inturned gripping flanges, and inturned matching flanges, the latter being recessed adjacent to the gripping flanges and enlarged to form reinforcements at the ends, substantially as shown and described.

jaws to said head, means on said head and
said side plates cooperating with said thumb
screw for rigidly and adjustably holding
one of said jaws to said head while permit-
ting the other jaw to swing on the pivotal
axis toward and from the rigid jaw, a spring
held between said side plates of the op-
posing jaw, a thumb screw passing through
the webs of said jaws between said side
10 plates for drawing them together against
the tension of the spring, the lower ends
of said jaws including laterally extended

web portions terminating at the bottom in
inturned gripping flanges, and inturned
matching flanges, the latter being recessed 15
adjacent to the gripping flanges and en-
larged to form reinforcements at the ends,
and an attachment having T-heads at the
ends of the same to be engaged by said jaws
at the reinforced ends of the lateral exten- 20
sions, said attachment adapted to be secured
to an article to be sustained.

HOWARD T. INGHRAM.
